PRY TYPE CLOSURE REMOVER WITH
PIERCING PRONG

Garnet L. Brown, Jamison, Pa.

Application June 12, 1952, Serial No. 293,085

1 Claim. (Cl. 81—3.47)

1

This invention relates to devices for breaking the seals and removing caps of covers of vacuum sealed containers, and in particular a handle having a rod extended therefrom with a pin spaced from the end of the rod and positioned to pierce a cover on a glass or other container, and a spring actuated jaw slidably mounted on the rod and positioned whereby a lower end thereof is adapted to grip the lower edge of the closure into which the prong spaced from the end of the rod is extended.

The purpose of this invention is to provide means for prying a lid or cap from a vacuum sealed container which, simultaneously with the prying action pierces the closure member to break the seal.

Various devices have been provided for opening vacuum or sealed jars and other containers, however, the method most commonly used is that of gripping the closure cap with the prong of a conventional can opener and it is sometimes difficult to insert the prong below the edge of a cap or closure. With this thought in mind this invention contemplates a vacuum sealed container opener in which the device is anchored on a cap or closure with a pin or prong extended through the closure member and wherein with the device anchored in this position a jaw is actuated to gripping relation with the closure by a spring whereby the elements coact to readily remove the closure from the container.

The object of this invention is, therefore, to provide means for forming a sealed container opener whereby the closure of the container is pierced to break the seal at the same time that the edge of the closure is gripped whereby with the seal broken the closure is readily removed.

Another object of the invention is to provide means for removing a closure of a sealed container in which a gripping jaw is adjustably mounted in relation to a piercing prong whereby the device is adapted for use on containers of different sizes.

A further object of the invention is to provide a sealed container opener that breaks the seal at the same time a closure of the opener is pried upwardly in which the device is of a simple and economical construction.

With these and other objects and advantages in view the invention embodies a substantially U-shaped gripping jaw slidably mounted on a rod and urged toward a prong extended through the rod by a spring on the rod and positioned between the jaw and the handle on the extended end of the rod.

2

Other features and advantages of the invention will appear from the following description taken in connection with the drawing, wherein:

Figure 1 is a side elevational view illustrating the improved sealed container opener showing the device positioned on the cap of a glass.

Figure 2 is a plan view of the opener also showing the device on a cap of a glass.

Figure 3 is an end elevational view looking toward the end of the opener on which the gripping jaw and piercing prong are positioned.

Figure 4 is a perspective view of the slide including the gripping jaw.

Referring now to the drawing wherein like reference characters denote corresponding parts the improved sealed container opener of this invention includes a rod 10 having a handle 11 on one end, a gripping jaw 12 positioned on the lower end of a slider 13, which is slidably mounted on the rod 10, a spring 14 positioned between the end of the handle 11 and the slider 13, and a piercing prong 15 spaced from the extended end of the rod and positioned to coact with the jaw 12 for piercing a cover as indicated by the numeral 16 and at the same time anchoring the opener as the jaw 12 engages the opposite side of the closure.

The slider 13 is provided with an upper flange 17 that is positioned to travel on the rod 10 and, as illustrated in Fig. 1, the flange 17 is inclined to support the slider with the jaw 12 extended upwardly whereby with the prong 15 positioned upon the cap or closure the spring 14 will urge the jaw 12 under the edge of the cap and as the handle 11 is moved upwardly the prong 15 will pierce the upper surface of the cap.

The flange 17 is provided with an opening 18 in which the end of the spring 14 is held whereby the spring may readily be compressed to withdraw the jaw 12 when positioning the opener on the cover or cap of a container.

With the parts arranged and assembled in this manner the opener may readily be used for container closures of different types and designs and with the vacuum relieved by piercing the cover with the prong the cap or cover is readily removable.

It will be understood that modifications within the scope of the appended claim may be made in the design and arrangement of the parts without departing from the spirit of the invention.

What is claimed is:

In a sealed container closure opener, the combination which comprises a handle having a rod extending therefrom, a prong mounted in

the rod spaced from the end opposite to that on which the handle is positioned and extending from one side of the rod, a substantially U-shaped slider having a flange positioned to travel on the rod and another flange, the end of which is beveled providing a gripping jaw for gripping the edge of a container closure with the prong piercing the closure, and a spring on the rod positioned between the handle and slider and connected to the flange of the slider positioned to travel on the rod.
